TURBINE AND CONDENSER CONSTRUCTION

Kenneth R. Stearns, Springfield, Pa., assignor to
Westinghouse Electric Corporation, East Pitts-
burgh, Pa., a corporation of Pennsylvania

Application November 6, 1946, Serial No. 708,109

5 Claims. (Cl. 60—95)

1

The invention relates to a turbine having an exhaust nozzle and a condenser into which steam is discharged by the nozzle and it has for an object to provide apparatus of this character with means for supporting the turbine on the condenser and with a joint connecting the exhaust nozzle to the condenser and constructed and arranged to provide for relative movement of the nozzle and the condenser in the direction of length of the nozzle and to hold the latter against lateral movement so that it cooperates with the supporting means to confine the turbine axis against transverse movement by holding it vertically and horizontally.

Another object of the invention is to provide a turbine and a condenser carried by a bedplate or supporting structure with an exhaust nozzle connection between the turbine and the condenser.

A further object of the invention is to provide for the aforesaid supporting means accommodating for radial and axial expansion of the turbine with the joint arranged to hold the exhaust end of the turbine against axial movement.

A further object of the invention is to provide a turbine supported on a condenser, and wherein the supporting means at the exhaust end is subject to temperature changes which are relatively small as compared to temperature changes of the nozzle for exhausting steam from the turbine into the condenser, together with a diaphragm connecting the exhaust nozzle and the condenser and positioned so that it is flexible in the direction of length of the nozzle and holds the latter laterally in relation to the condenser, whereby the nozzle is free to expand and contract without disturbing the alignment of the adjacent bearing while the exhaust end of the turbine is held against axial and transverse movements.

Another object of the invention is to provide a condenser and a turbine wherein the turbine includes a casing having an exhaust nozzle for discharging steam into the condenser, a pedestal, a vertically flexible tie plate connecting the inlet end of the casing and the pedestal, a pair of columns for supporting the exhaust end of the casing on the condenser, and axially flexible plate means for supporting the pedestal on the condenser together with a diaphragm connected to the condenser and welded to the exhaust nozzle, the diaphragm being flexible in the direction of length of the nozzle and holding the latter laterally and cooperating with said columns and the axially flexible plate means to confine the turbine axis against transverse movement by

2

holding it vertically and horizontally and, with the columns and the axially flexible plate means accommodating for radial and axial expansion of the turbine, to hold the exhaust end of the turbine laterally and axially.

The foregoing and other objects are effected by the invention as will be apparent from the following description and claims taken in connection with the accompanying drawings, forming a part of this application, in which:

Fig. 1 is a side elevational view of the improved unitary power plant;

Fig. 2 is a plan view of the apparatus shown in Fig. 1;

Fig. 3 is a sectional view taken along the line III—III of Fig. 1;

Fig. 4 is a sectional detail view of the joint structure connecting the turbine nozzle and the condenser; and

Fig. 5 is a view similar to Fig. 4 but showing a modified joint structure.

In the drawing, there is shown a power plant including a condenser 5 constituting the foundation or support for the turbine, at 6, and the generator 7 driven thereby. The turbine and the generator have their axes aligned and arranged parallel to the condenser so that the latter may function to the best advantage as a support. The turbine 6 comprises a casing 8 and a spindle 9 held in proper relation thereto by the exhaust end journal bearing 10 carried by the casing and by the journal bearing 11 and thrust bearing 12 carried by the pedestal 14 connected to the casing in the manner hereinafter described. The condenser has an exhaust inlet opening 15 and the turbine has an exhaust nozzle 16 for discharging exhaust steam into the condenser.

As more particularly described and claimed in my application Serial No. 708,880, filed November 9, 1946, now Patent No. 2,464,357, the condenser 5 is formed with supporting girder structures 18 at its sides, the girder structures serving to support the condenser, the turbine, and the generator from the foundation.

The generator is supported by columns 19 whose lower ends are carried by and connected to the girder structures 18. Similarly, the exhaust end of the turbine is supported by and connected to the upper ends of columns 20 whose lower ends are supported by and connected to the girder structures, the upper ends of such columns being connected to the turbine casing 8 at the horizontal joint.

At its inlet end, the turbine casing 8 is formed with feet 22 bearing on abutments 23 unitary

with the bearing pedestal 14 connected to the casing by a tie plate 25 positioned for flexing vertically.

The bearing pedestal 14 is carried by the upper edges of plates 26 and 27 whose lower edges are connected to the condenser, said plates extending in vertical planes normal to the turbine axis so as to be flexible in the direction of the latter.

The structure described supports the turbine so that it is free to expand radially and axially and the joint, at 28, more particularly herein-after described, cooperates with the condenser to hold the exhaust nozzle laterally and it thereby cooperates with the turbine-supporting means to confine the turbine axis against transverse movement by holding it vertically and horizontally.

At the exhaust end, as the exhaust nozzle 15 is connected to the condenser by the joint, at 28, herein-after described, the turbine casing is free to expand laterally or radially in all directions, the columns 20, which support the casing and hold the turbine axis vertically, being capable of flexing to the extent required.

At the inlet end, the turbine casing is free to expand radially, the connecting tie plate 25 flexing vertically and the feet 22 sliding horizontally on the abutments 23 to the extent required. In this connection, the hold-down bolts 29 for the feet extend through larger openings in the latter so that the feet are capable of being displaced relative to the bolts, as is well known in the art.

With respect to axial expansion of the turbine, as the exhaust end of the casing is held by means of the columns 20 and by the exhaust nozzle and condenser joint structure, at 28 and herein-after described, provision is made for such expansion at the inlet end, expansion of the casing acting through the tie plate 25 to move the bearing pedestal 14 axially, the supporting plates 26 and 27 flexing axially to the required extent. While the plates 26 and 27 are capable of flexing to accommodate axial movement, such plates are stiff or very rigid in their planes with the result that they cooperate to hold the turbine axis transversely.

As the exhaust end of the turbine may be subject to temperature changes, as when starting before the vacuum has built up in the condenser or when, for any reason, the vacuum is lost and the turbine runs non-condensing, the exhaust nozzle is subject to such temperature changes, while the columns 20, being exposed to ambient air, or being in poor heat conductive relation to the exhaust nozzle, undergo little, if any, change in temperature. Therefore, if the exhaust end of the turbine were supported by the exhaust nozzle, changes in length of the latter would disturb the position of the turbine axis vertically. On the other hand, if the exhaust end of the turbine were supported and connected to the supporting structure both by the nozzle and by the columns, the differential expansion and contraction thereof would result in destructive stresses of the structure or distortion thereof and disturbance of the position of the turbine axis.

In order that the exhaust end of the turbine may be supported with the turbine axis held vertically, while at the same time the exhaust nozzle is permitted to expand and contract in the direction of its length, there is provided the joint, at 28, connecting the exhaust nozzle to the condenser. In addition to accommodating for length-wise contraction and expansion of the exhaust nozzle 16, the joint holds the nozzle

against lateral movement with the result that it is effective to hold the casing axially at the exhaust end and to hold the turbine axis axially and horizontally, it being remembered that the casing and the turbine spindle are rotatably connected by the bearing pedestal thrust bearing 12, in consequence of which, with the exhaust end of the casing held axially and with axial expansion of the casing, the inlet end of the casing and the pedestal move axially.

Preferably, the joint, at 28, is comprised by an annular metallic diaphragm 31 whose outer edge is secured to the condenser and whose inner edge is joined to the nozzle, the diaphragm deflecting to accommodate for lengthwise expansion and contraction of the nozzle and has great stiffness or strength in its plane, or laterally of the exhaust nozzle, giving it the capability of holding the latter so that the turbine is held axially at the exhaust end. As the means already described for supporting the turbine accommodates for radial and axial expansion thereof, holding of the exhaust nozzle laterally coacts with the supporting means to confine the turbine axis against lateral movement by holding it vertically and horizontally.

The condenser is formed with an annular seat 32 about the exhaust inlet opening 15 and the diaphragm is shown as being welded both to the seat and to the nozzle. The diaphragm facilitates final assembly for the reason that, with it connected to the seat in any suitable manner, cumulative dimensional errors may be absorbed by the weld connecting its inner edge to the exhaust nozzle.

As shown in Figs. 1 to 4, inclusive, the seat 32 is provided by a circumferential or ring member 34 welded, at 35, to the condenser and the diaphragm 31 is connected to the member 34 by exterior and interior welds 36 and 37. The inner edge of the diaphragm is welded, at 38, to the exhaust nozzle. With this construction, the weld 38 provides for absorption of errors, as just described.

Fig. 5 is similar to Fig. 4 except that, instead of the weld 38 connecting the diaphragm to the nozzle, a weld 39 connects the diaphragm to the joint ring 40 connected by screws 41 to the ring 42 welded, at 38a, to the nozzle. With the ring 34 welded to the condenser and the diaphragm 31 welded to the ring, as before, and with the ring 40 welded to the diaphragm and connected by the screws to the ring 42, the latter is welded to the nozzle so that cumulative dimensional errors may be absorbed. The modified joint construction has the advantage that the exhaust nozzle may be disconnected from the condenser merely by removal of the screws 41 without cutting the diaphragm or welds.

While the condenser and its side girders, illustrated and described, constitute a condenser aggregate, it is to be understood that "condenser," as used in the claims, has the significance of any condenser capable of carrying the turbine-supporting means herein described and claimed. Also, it is to be understood that "annular," as descriptive of the shape of the diaphragm, has the significance of conformity to the shell opening and to the nozzle, that is, it may be circular, oblong, or any suitable shape.

While the invention has been shown in several forms, it will be obvious to those skilled in the art that it is not so limited, but is susceptible of various other changes and modifications without departing from the spirit thereof.

What is claimed is:

1. In a power plant, a horizontal condenser having a shell provided with an exhaust steam inlet opening, a horizontal turbine provided with a substantially vertical exhaust nozzle, means for supporting the turbine at its inlet and exhaust ends on the condenser shell and providing for axial and radial expansion thereof, said supporting means at the exhaust end being subject to temperature changes which are relatively small in relation to temperature changes of the exhaust nozzle, and an expansion joint connecting the exhaust nozzle and the condenser shell so that exhaust steam issuing from the nozzle passes through said inlet opening into the condenser shell said expansion joint including an annular diaphragm whose outer edge is secured in sealed relation with respect to the shell and about the exhaust steam inlet opening and whose inner edge is secured in sealed relation to and about the lower end of the nozzle, said diaphragm being horizontal to provide flexibility in a vertical direction enabling the nozzle to move vertically relative to the shell and to provide horizontal stiffness to hold the turbine axially and, in cooperation with said supporting means, to hold the turbine axis vertically and horizontally.

2. In a power plant, a horizontal condenser having a shell provided with an inlet opening for exhaust steam; a horizontal turbine including a casing provided with an exhaust nozzle, a bearing pedestal, and means connecting the inlet end of the turbine and the pedestal and comprising a vertically flexible tie plate and feet unitary with the casing and bearing on the pedestal; means for supporting the casing and the pedestal on the condenser shell and cooperating with said connecting means to provide for radial and axial expansion of the turbine; said means comprising columns connected to the exhaust end of the casing and to the condenser shell and axially flexible plate means connected to the condenser shell and to the pedestal; and an expansion joint connecting the exhaust nozzle and the condenser shell so that exhaust steam issuing from the nozzle passes through the inlet opening into the condenser shell; said expansion joint including an annular diaphragm whose outer edge is secured in sealed relation with respect to the shell and about the exhaust steam inlet opening and whose inner edge is secured in sealed relation to and about the lower end of the nozzle; said diaphragm being horizontal to provide flexibility in a vertical direction enabling the nozzle to move vertically relative to the shell and to provide horizontal stiffness to hold the turbine axially and, in cooperation with said supporting means, to hold the turbine axis vertically and horizontally.

3. Apparatus as claimed in claim 2 wherein the expansion joint includes an outer ring welded to the outer edge of the diaphragm and to the shell and a welded connection for joining the inner edge of the diaphragm and the exhaust nozzle.

4. Apparatus as claimed in claim 2 wherein the expansion joint includes an outer ring welded to the outer edge of the diaphragm and of the shell, a pair of superposed rings, one of which is welded to the inner edge of the diaphragm and the other of which is welded to the exhaust nozzle, and screws compressively engaging the superposed rings in sealing relation.

5. In a horizontal power plant, a turbine including a casing provided with an exhaust nozzle, a horizontal condenser extending parallel to the turbine axis and having a shell provided with an inlet opening for exhaust steam, means for supporting the turbine casing on the condenser shell and carrying the turbine reaction torque, said means including legs connected at their ends to the exhaust end of the turbine and to the condenser, said legs being structurally separate from the exhaust nozzle so as to be subject to the temperature of ambient air while the nozzle is subject to the temperature of the exhaust, and an expansion joint connecting the exhaust nozzle and the condenser shell, so that exhaust steam issuing from the nozzle flows through said inlet opening into the condenser shell said expansion joint including an annular diaphragm whose outer edge is secured in sealed relation with respect to the shell and about the exhaust steam inlet opening and whose inner edge is secured in sealed relation to and about the lower end of the nozzle, said diaphragm being horizontal to provide flexibility in a vertical direction enabling the nozzle to move vertically relative to the shell and to provide horizontal stiffness to hold the turbine axially and, in cooperation with said supporting means, to hold the turbine axis vertically and horizontally.
